PAUL G. WIEGERT, OF CLEVELAND, OHIO, ASSIGNOR TO THE W. S. TYLER COMPANY,
OF CLEVELAND, OHIO, A CORPORATION OF OHIO.

ELEVATOR-DOOR-OPERATING MECHANISM.

1,163,578.

Specification of Letters Patent.

Patented Dec. 7, 1915.

Application filed January 28, 1915. Serial No. 4,831.

To all whom it may concern:

Be it known that I, PAUL G. WIEGERT, a citizen of the United States, and a resident of Cleveland, in the county of Cuyahoga and State of Ohio, have invented a new and useful Improvement in Elevator-Door-Operating Mechanism; and I do hereby declare the following to be a full, clear, and exact description thereof.

10 The present invention relates to new and useful improvements in operating mechanism for elevator doors, and as its principal object aims to provide a device of this character which is especially adapted for use in connection with elevator doors of the type employing two slidably mounted door sections arranged to move in the same direction when being opened or closed.

15 The primary object of the invention is the provision of a speed controlling device for the door sections which is simple as regards construction, will be durable and efficient in service and may be applied to standard elevator doors of the type specified without requiring any material changes or alteration in construction thereof.

20 The above, and other incidental objects of a similar nature, are accomplished by such means as are illustrated in the accompanying drawings, described in the following specification, and then more particularly pointed out in the claims, which are appended hereto and form a part of this application.

25 Referring to the drawings, wherein I have illustrated the preferred embodiment of my invention as it is reduced to practice, and throughout the several views of which similar reference numerals designate corresponding parts: Figure 1 is a front elevation showing the upper portion of the door sections and the casing, and illustrating the speed controlling device in operative relation to the hangers of the door; Fig. 2 is a detail view and front elevation of the speed controlling device in connection with the hangers of the two door sections; Fig. 3 is a vertical section on the line 3—3 of Fig. 1; and Fig. 4 is a diagrammatical view illustrating the principle on which the speed controlling device of this invention is designed.

30 As shown in the accompanying drawings the door to which this invention is applied is of standard construction including as it does a pair of door sections A and B and a

pair of tracks C and D from which the doors are slidably suspended.

In the following description it will be assumed that the doors A and B, as shown in Fig. 1, are in closed position, and that they are to be moved in the direction of the arrow when being opened. The door A will therefore be hereinafter referred to as the fast door, and the door B as the slow door, since the first mentioned door must travel a considerably greater distance when being moved into either open or closed position than the door B.

The track bars C and D are arranged in parallel spaced relation to each other, as shown in Fig. 3. Each terminal of the member D is supported by a hub 10 into which bolts, indicated by dotted lines at 11, are passed for securing the terminals of the member 9 thereto. Hubs 12 and securing bolts indicated by dotted lines at 13 are employed in supporting the track bar C. The hubs 10 and 12 are cast on a bracket plate 14 which is secured by rivets or any other desired fastening device to the upper horizontal frame member 15 of the elevator door casing. Mounted for movement over the tracks D are a plurality of rollers 16 each of which is provided with a peripheral V-shaped groove 17. In order that the roller 16 may move as a unit over the track D I employ a pair of connecting bars 18 and 19 which are disposed on opposite sides of the rollers and secured to one of these members by means of bolts or axles indicated at 20. A plurality of rollers 21 which are connected as a unit by a pair of connecting bars 22 and 23 and axle bolts 24 are mounted for movement over the track bar C.

35 The door A is slidably suspended by means of a pair of hanger straps 25 and 26. The upper terminals of these inner straps are connected by bolts 27 to the slidable hanger bars 28. This bar 28 is mounted for movement over the rollers 21 as is best shown in Fig. 3.

40 In order to prevent the accidental outward displacement of the member 28 there is provided an L-shaped guard plate 29 which is secured in the proper position by means of supporting brackets 30 which extend horizontally from the member 15. The depending vertical portion of this member 29 is disposed on the outer face of the member 28. As a means for guarding against

the inward displacement of the member 28 there is provided a pair of stop screws 31 which are threaded through the upper terminals of the members 25 and 26. The inner ends of these members 31 are adapted to engage with the vertical portion of the member 29 in case the member 28 starts to jump from the rollers 21.

The door B is suspended from the hanger bar 32 by means of the hanger straps 33 and 34. These members 33 and 34 are connected by bolts 35 to the member 32 and are arranged in spaced relation thereto as are the members 25 and 26 disposed with respect to the member 28. The hanger bar 32 is, as shown best in Fig. 3, mounted for movement over the rollers 16 being disposed with its lower edge in the peripheral groove thereof. A guard plate 36 and a stop screw 37 similar in construction, function and arrangement to the members 29 and 31, are provided for the hanger bar 32.

As will be hereinafter more fully disclosed, it is necessary in the present invention that the hanger bar 32 be actuated by the movable unit composed of the rollers 21 and connecting bars 22, and for this purpose I employ a connecting plate 37. This connecting plate 37 includes a horizontal portion 38 and two vertical portions 39 and 40 which extend in parallel planes. The member 40 is secured to the track 32 while the vertical portion 39 is secured to the inner connecting bar 23.

The speed controlling device of this invention comprises a sprocket wheel S which is disposed between the connecting bars 22 and 23 and is journaled for rotation on a spindle or axle 41. The member S is of a diameter greater than the diameter of the rollers 16 and 21, and is provided with a plurality of circumferentially spaced, radially extending notches 42. A series of longitudinally spaced pins 43 project from the outer face of the hanger bar 28 adjacent the lower edge thereof. From the outer face of the track bar C and at the upper edge portion thereof project a plurality of pins 44 which are longitudinally spaced and are similar to the members 43. The spaces between the individual pins of the series 43 and the series 44 are equal to the chords of the arcs separating the several notches 42 of the member S. As will be readily seen upon reference to Figs. 1 and 2 the notches 42 are adapted to receive the pins 43 and 44 when the door A is moved in either direction.

Reference should now be had to Fig. 4 in which the principle upon which this invention is diagrammatically illustrated. In this figure the point X on the smaller circle represents a point on the periphery of the rollers 21, while the point Y on the larger circle indicates a point in the periphery of the sprocket wheel S. Obviously if the points

X and Y are fixed as regards their relation to each other and are rotated about the axis Z, the distance traveled by the point Y during one complete revolution will be considerably greater than the distance traveled by the point X. Thus in the case of the sprocket wheel S and the rollers 21 it will be observed that a point in the periphery of the member S will travel a greater distance for each revolution of this member than will be traveled by a point in the periphery of the rollers 21. Since the pins 43 represent a point in the periphery of the member S and since the hanger bar 32 of the slow door B is actuated by the connecting bar 22 it is obvious that when the operator moves the fast door A into either open or closed position the movement of this door will be communicated to the slow door B at a less speed. In this connection it should be noted that the speed of the hanger bar 28 and consequently of the fast door A is commensurable by the speed of a point in the periphery of the sprocket wheel S, while the speed of the hanger bar 32 and consequently of the slow door B is commensurable by the speed of a point in the periphery of the roller 21.

In reduction to practice, I have found that the form of my invention, illustrated in the drawings and referred to in the above specification as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to when required, without sacrificing any of the advantages of my invention, as defined in the appended claims.

What is claimed is:

1. In a sliding door construction, in combination, a fast door and a slow door, a rail connected with said slow door, a track beneath said rail, rollers between said rail and track, a second fixed track, rollers on said second track, a carriage rotatably supporting said rollers and connected with said slow door, and a second rail supported on said second named rollers and connected with 110 said fast door.

2. In a sliding door construction, in combination, a fast door and a slow door, a rail connected with said slow door, a track beneath said rail, rollers between said rail and track, a second track, rollers on said second track, a carriage rotatably supporting said rollers and connected with said slow door, a second rail supported on said second named rollers and connected with said fast door, a speed-controlling sprocket rotatably mounted in said carriage, and sprocket engaging projections on said last named rail and track.

3. In a sliding door construction, in combination, a fast door and a slow door, a 130

hanger extending upwardly from said slow door, a rail secured to said hanger, a track beneath said rail, rollers between said track and said rail, a second fixed track, rollers on 5 said second track, a carriage for rotatably supporting said rollers, a bracket connected between said rail and said carriage, a second rail supported on said second named rollers, and a hanger extending upwardly from said 10 fast door and secured to said second named rail.

4. In a sliding door construction, in combination, a fast door and a slow door, a hanger extending upwardly from said slow 15 door, a rail secured to said hanger, a track beneath said rail, rollers between said track and said rail, a second track, rollers on said second track, a carriage for rotatably supporting said rollers, a bracket connected between 20 said rail and said carriage, a second rail supported on said second named rollers, a hanger extending upwardly from said fast door and secured to said second named rail, a sprocket rotatably mounted in said carriage, and sprocket-engaging projections extending outwardly from said last named rail and track.

5. In a sliding door construction, in com-

bination, a door frame, a fast door and a slow door slidably associated with said 30 frame, a hanger extending upwardly from said slow door, a rail secured to said hanger, an abutment extending from said hanger toward said rail, an engaging member secured to said door-frame and disposed between 35 said abutment and said rail, a track secured to said door frame beneath said rail, rollers between said track and said rail, a second track secured to said door frame and disposed parallel with said first named track, 40 rollers on said second named track, a carriage for rotatably supporting said rollers, connection means between said carriage and said rail, a second rail supported on said second named rollers, a hanger extending 45 upwardly from said fast door and connected with said second named rail, and means for preventing said second named rail from leaving its position on said rollers.

In testimony whereof, I, the said PAUL G. 50 WIEGERT, have hereunto set my hand.

PAUL G. WIEGERT.
